Specification for Design.

Patented Nov. 23, 1920.

Application filed December 31, 1919. Serial No. 348,686. Term of patent 7 years.

To all whom it may concern:

Be it known that I, BESSIE A. HAINES, a citizen of the United States, residing in the town of Bristol, county of Elkhart, Indiana, have invented a new, original, and ornamental Design for a Doll, of which the following is a specification, reference being had to the accompanying drawing, forming a part hereof.

On the drawing, Figure 1 is a side elevation of the doll showing my new design; Fig. 2 is a front elevation; and Fig. 3 is a rear elevation thereof.

I claim:

The ornamental design for a doll, as shown.

In testimony whereof I have hereunto affixed my signature this 22d day of December, 1919.

BESSIE A. HAINES.
